US00D621935S

(12) **United States Design Patent**
Cole et al.

(10) **Patent No.:** **US D621,935 S**
(45) **Date of Patent:** **** Aug. 17, 2010**

(54) **STETHOSCOPE CLEANING ASSEMBLY**

(76) Inventors: **Michael R. Cole**, 10 Wedgewood Dr., Stratham, NH (US) 03885; **Mathew Cardinali**, 28A Dearborn St., Portsmouth, NH (US) 03801; **James M. Sellers**, 83 Garrison Dr., Eliot, ME (US) 03903; **Michael Perlman**, 2210 SW. 102nd Dr, Davie, FL (US) 33324; **Keith Rubin**, 2100 N. Ocean Blvd., Unit #501, Fort Lauderdale, FL (US) 33305

(**) Term: **14 Years**(21) Appl. No.: **29/310,257**(22) Filed: **Aug. 5, 2008****Related U.S. Application Data**

(63) Continuation-in-part of application No. 12/079,077, filed on Mar. 24, 2008, now Pat. No. 7,503,335, which is a continuation-in-part of application No. 11/728, 207, filed on Mar. 23, 2007, now Pat. No. 7,406,973.

(51) **LOC (9) Cl.** ..... **24-02**(52) **U.S. Cl.** **D24/134**

(58) **Field of Classification Search** D24/134, D24/135, 165, 140; D6/567; 181/131-137; 600/528

See application file for complete search history.

CLAIM

The ornamental design for a stethoscope cleaning assembly, as shown and described.

DESCRIPTION

FIG. 1 is a front perspective view illustrating my design for a stethoscope cleaning assembly;

FIG. 2 is a front view thereof;

FIG. 3 is a left side view thereof;

FIG. 4 is a top view thereof;

FIG. 5 is a right side view thereof;

FIG. 6 is a bottom view thereof; and,

FIG. 7 is a rear view thereof; and,

FIG. 8 is a rear perspective thereof.
